UNITED STATES PATENT OFFICE.

ISAAC HUBERT WEBB, OF BROOKVILLE, PENNSYLVANIA.

COMBINATION-BARREL FOR SWEEPING COMPOUNDS.

1,261,660.

Specification of Letters Patent.

Patented Apr. 2, 1918.

Application filed April 11, 1917. Serial No. 161,376.

To all whom it may concern:

Be it known that I, ISAAC HUBERT WEBB, a citizen of the United States, residing at Brookville, in the county of Jefferson and

5 State of Pennsylvania, have invented certain new and useful Improvements in Combination-Barrels for Sweeping Compounds, of which the following is a specification.

My invention relates to a combination 10 storage and shipping barrel adapted more particularly for the storing and shipping of sweeping compounds, and it consists in the constructions, combinations and arrangements herein described and claimed.

15 An object of my invention is to provide a receptacle for storing and shipping sweeping compounds which contain considerable quantities of oil, and it consists in utilizing any ordinary wooden barrel by fixing a 20 metal pan in the bottom of the barrel to catch the oil from the sweeping compound which naturally sinks toward the bottom, and prevents the leakage thereof out of the barrel.

25 Another object of the invention consists in packing a tube in the barrel with the sweeping compound, the purpose of the tube being to obtain access to the sweeping compound near the bottom of the barrel, the 30 tube being adapted to be raised or lowered so that quantities of sweeping compound having the desired percentage of oil may be scooped out.

Another object of the invention is to provide 35 a tube which, as above described, is packed in with the sweeping compound and permits access to the material near the bottom of the barrel, the tube having a flange at the top so that the user's hands will not 40 be cut in raising or lowering the tube.

Other objects and advantages will appear from the following specifications, reference being had to the accompanying drawing in which:

45 Figure 1 is a central vertical section illustrating the application of my invention.

Fig. 2 is a detail view of the pan showing the tapered sides.

Fig. 3 is a detailed perspective view of 50 the tube,

Fig. 4 is a detailed perspective view showing how the sweeping compound may be scooped from near the bottom of the barrel through the tube.

55 In carrying out my invention I provide a barrel 1. The barrel 1 may be made espe-

cially for the purpose of either iron or steel, or it may be an ordinary cracker or sugar barrel. In the latter instances, the staves of the barrel are held together by the hoops 60 2 at the top and bottom. The barrel 1 has the ordinary bottom which may be either left in place as illustrated in the drawing, or may be removed.

A sweeping compound S is packed in the 65 barrel 1 for either storing the compound or shipping it. The sweeping compound S contains oil and when it is packed in the ordinary wooden stave barrel, the oil which naturally settles at the bottom of the barrel, 70 leaks out and leaves the compound dry and worthless.

A metal pan 3 is placed in the bottom of the barrel to catch the settled oil and prevent leakage thereof out of the barrel. The 75 wall of the pan is tapering as shown in Figs. 1 and 2 of the drawing, for the purpose of permitting the wedging of the pan tightly in position.

The tapered sides of the pan 3 permit the 80 tight wedging of the pan in place so that accidental displacement of the pan is impossible.

The sweeping compound S is then packed into the barrel 1. As the material is packed 85 into the barrel and gets deeper and deeper, the tube 4 is located in position and the packing operation of the barrel is continued. The sweeping compound S is now packed around the tube 4, until the flange 5 is 90 reached. It may also be desirable to first completely pack the barrel 1 with the sweeping compound S, and then thrust the tube 4 down through the material until the flange 5 rests on the surface thereof. 95

The flange 5 of the tube 4 makes it easier to push the tube farther down into the material because a broader surface is presented thereby which prevents the cutting of the hands. It has been found in practice that 100 the oil or grease in sweeping compounds settles on the bottom of the barrel and the material near the top consequently becomes dry and in that state, unfit for use.

This dry material is removed from the top 105 and mixed with another quantity of the sweeping compound which is gotten from near the bottom of the barrel by scooping it up through the tube 4.

The sweeping compound thus scooped up 110 through the tube 4 is naturally saturated with oil. As the material is used from the

top, the tube 4 is pushed farther down until the flange 5 again rests on the surface of the sweeping compound. The tube 4 is also used to remove the oily compound from the 5 bottom of the barrel where a greasy compound is desired for the purpose of oiling the floor. In such instances, the greasy compound is left on the floor over night and is swept up on the following morning, when 10 it can be used again for sweeping and cleaning purposes.

It will also be understood that quantities 15 of the sweeping compound having the desired quantity of oil or grease can be gotten by simply raising or lowering the tube 4. Thus should it be required to use a quantity 20 of sweeping compound rich in oil, the tube 4 is pushed far down into the mass and material is scooped up from near the bottom 25 of the barrel. Similarly, should a quantity of the sweeping compound having a lesser quantity of oil be desired, the tube 4 is pulled higher out of the mass and a quantity of the material scooped up from about the center of the barrel.

While the construction and arrangement 30 of the device is that of a generally preferred form, obviously modifications and changes therein may be made without departing from the spirit of the invention or the scope of the claims.

I claim:

1. In a device as described, a receptacle for storing and shipping a moist substance,

and an open ended cylinder normally separate from the receptacle, but fixed in position therein, by packing said cylinder into said substance, said cylinder permitting reaching portions of the substance richer in moisture, near the bottom end of the cylinder. 35 40

2. A shipping receptacle for oily sweeping compounds, consisting of a barrel, a relatively deep pan located in the bottom of the 45 barrel for preventing the leakage of settled oil, the pan having a tapered wall whereby the pan is wedged in the barrel, and a tube packed in the barrel with the sweeping compound heavier in oil nearer the pan, the tube having a flange for resting on the surface of the compound and preventing the cutting of the hands in pushing the tube farther into the compound. 50

3. A receptacle for storing and shipping 55 moist substances, comprising a barrel for containing said substance, a separate open ended tube adapted to be pushed down into the substance to remove the substance from the bottom of the barrel, and a flange formed on the upper edge of the tube adapted to rest upon the surface of the substance and prevent cutting the hands in pushing the tube in place. 60
